UNITED STATES PATENT OFFICE.

WILLIAM M. HENSON, OF KANSAS CITY, MISSOURI.

DESIGN FOR A KITCHEN-CABINET.

SPECIFICATION forming part of Design No. 32,115, dated January 16, 1900.

Application filed November 20, 1899. Serial No. 737,705. Term of patent 14 years.

To all whom it may concern:

Be it known that I, WILLIAM M. HENSON, a citizen of the United States, and a resident of Kansas City, in the county of Jackson and State of Missouri, have invented and produced a new and original Design for Kitchen-Cabinets, of which the following is a specification.

My invention relates to kitchen-cabinets; and my object is to produce a new and useful design for the same.

Referring to the accompanying drawing, which represents a perspective view of a kitchen-cabinet embodying my design, it will be noticed that the leading or material feature of the same consists in its novel and peculiar configuration, the base or lower portion being of oblong rectangular form and the body or upper portion of substantially oblong rectangular form with its ends (when viewed in plan) describing a semicircle and with its front side or face depressed or sunken to provide a recess or panel extending from its lower to its upper margin; also, in the representation of a small rectangular door at the lower end of said recess or panel and of a rectangular door of greater area, the latter being also seated in said recess or panel and superposed with reference to the former and provided with a panel representation of a mirror.

Minor features of the design reside in the mitered corners of the oblong rectangular base, the representation of hinges at opposite ends of said base, and the representation of knobs projecting forwardly from the face of the base near its center; also, in the representation of semicircular hinged doors at the top of the body and of knobs projecting therefrom; also, in the representation of circular screw-cap-like figures at the top of the body between said representations of the semicircular doors; also, in the loop-like figures projecting from the rear upper margin of the body, in the paneled and forwardly-diverging sides of the recessed or paneled front side of

the body, and in the knob-like projections from the representations of doors seated in said recess or panel; also, in the representation of superimposed segmental plates at one side and lower end of the cabinet-body, of a 50 turn-button overlapping said plates, and of a pin-like figure projecting outwardly from the upper of said plates.

In detail, 1 designates the oblong rectangular base. 55

2 designates the oblong rectangular body, having semicircular ends 3.

4 designates the recess or panel in the front side of the body.

5 designates the lower-door, and 6 the upper-door representation, and 7 the mirror representation of said large door. 60

8 designates the mitered corners of the base, 9 the hinge-like, and 10 the knob like, figures of the base. 65

11 designates the semicircular door-like figures, and 12 the representation of knobs for said doors.

13 designates the circular cap-like figures, and 14 the loop-like figures, and 15 the forwardly-diverging sides of the recessed or paneled front side of the body. 70

16 17 represent knobs for the door-like figures 4 and 5, respectively.

18 19 respectively designate the segmental 75 plates at one side and lower end of the cabinet-body; 20, the representation of a turn-button overlapping said plates, and 21 the pin-like figure projecting from the plate 18.

Having described my invention, what I claim as new, and desire to secure by Letters Patent, is—

The design for a kitchen-cabinet, as herein shown and described.

In testimony whereof I affix my signature 85 in the presence of two witnesses.

WILLIAM M. HENSON.
